UNITED STATES PATENT OFFICE.

CLARENCE S. NATHAN, OF NEW YORK, N. Y.

DESIGN FOR A CALENDAR.

SPECIFICATION forming part of Design No. 14,026, dated July 3, 1883.

Application filed December 4, 1882. Term of patent 7 years.

To all whom it may concern:

Be it known that I, CLARENCE S. NATHAN, a citizen of the United States of America, residing at New York, in the county of New York and State of New York, have invented 5 certain new and useful Improvements in Designs for Calendars, of which the following is a specification, reference being had therein to the accompanying drawing.

10 This design is intended for a calendar; and it consists in a configuration representing a sea view with a steamship and pilot-boat, having characters thereon indicating the days of the week and month, and the name of the 15 month appearing through openings represented in the design.

I prefer to arrange said design substantially in the manner shown in the accompanying drawing, in which A represents a steamship 20 provided with the usual sails, &c., and B is a pilot-boat. At the bow of the steamship is shown a flag, C, having an opening, c, represented through it, in which opening appears the name of the month. At the stern another 25 flag, D, is shown, also having an opening, d, represented through it, in which appears the name of the day of the week. An opening, b, is also represented in one of the sails of the pilot-boat B, in which opening appears a number 30 representing the day of the month.

A ventilator is shown near the funnel of the steamer, in the mouth of which is an eyelet, which forms the bearing for disks for the day of the week or month, to be placed behind the design, and at E is shown another eyelet or 35 rivet, forming the center of the month-disk.

It is evident that the configuration of this design may be varied considerably without departing from the essential features thereof.

What I claim as new is—

40 1. A design for a calendar, consisting of a representation of a steamship, on portions of which appear characters representing dates, as shown.

2. The design for a calendar herein shown, 45 consisting of a steamship showing openings through flags, in which appear the name of the month and the day of the week, and a pilot-boat having an opening represented in one of its sails, through which appear figures representing the day of the month, as set forth. 50

In testimony whereof I affix my signature in presence of two witnesses.

CLARENCE S. NATHAN.
